UNITED STATES PATENT OFFICE.

FRANCIS S. RUTSCHMAN, OF PHILADELPHIA, PENNSYLVANIA.

APPARATUS FOR MIXING AND KNEADING SOAP.

SPECIFICATION forming part of Letters Patent No. 628,186, dated July 4, 1899.

Application filed October 31, 1898. Serial No. 695,006. (No model.)

To all whom it may concern:

Be it known that I, FRANCIS S. RUTSCHMAN, a citizen of the United States, residing in the city and county of Philadelphia, State of Pennsylvania, have invented a new and useful Improvement in Apparatus for Manufacturing Soap, which improvement is fully set forth in the following specification and accompanying drawings.

10 My invention relates to an improved construction of apparatus for manufacturing soap which is especially designed for mixing perfumery, coloring-matter, &c., into and thoroughly commingling the same with the soap; and it consists especially of a series of rolls arranged in staggered order, the upper series of said rolls being adapted to rotate faster than the lower series and to have scraping devices located in proximity thereto, whereby 15 the soap is prevented from passing around said upper rollers.

It also consists of novel means for adjusting the scrapers and their adjuncts.

It also consists of a novel construction of 25 deflecting devices, whereby the soap is properly deflected and concentrated during its passage between the rolls.

It further consists of novel details of construction, all as will be hereinafter fully set 30 forth and particularly pointed out in the claims.

Figure 1 represents a side elevation of an apparatus for manufacturing soap embodying my invention. Fig. 2 represents a plan 35 view of Fig. 1. Fig. 3 represents a section on line $\alpha\alpha$, Fig. 2. Fig. 4 represents a front elevation of one of the upper rolls, showing a plurality of scrapers adjacent thereto and means for supporting and adjusting said scrapers. Fig. 5 represents a plan view of the 40 underside of one of the upper rollers, showing also the deflecting devices applicable thereto.

Similar numerals of reference indicate corresponding parts in the figures.

45 Referring to the drawings, 1 designates the main shaft of the apparatus, the same having, if desired, tight and loose pulleys mounted thereon, as is customary.

2 designates a pinion carried by the shaft 50 1 and meshing with the gear 3, which is mounted on the shaft 4, which latter carries

the pinion 5, which meshes with the gear 6, which is mounted on the shaft 7.

8 designates a gear mounted on the shaft 7 on the end opposite to the gear 6 and in mesh 55 with the gear 8, which is mounted on the shaft 10, the latter carrying a gear 11, which is in mesh with the gear 12, which is mounted on the shaft 13.

14 designates a gear mounted on the shaft 60 4 and in mesh with the gear 15, mounted on the shaft 16, which latter carries the gear 17, which meshes with the gear 18, which is mounted on the shaft 19, the opposite extremity of the latter having a sprocket-wheel 65 20, around which passes the sprocket-chain 21, by means of which power is transmitted to a sprocket-wheel 22, which is mounted on the shaft 23, the latter carrying the roller 24, around which passes an apron or endless band 70 25, the latter also encircling the roll 26, located at the front of the machine, said roll being mounted upon a shaft or journals 27, and power being transmitted from the roll 24 to the roll 26 by means of the sprocket-chains 75 28, which latter pass around the sprocket-wheels 29, mounted on said shaft 27, and the sprocket-wheels 22 $\times$ on the shaft 23.

30, 31, and 32 designate an upper series of rolls, which are composed of any suitable material and mounted on the shafts 10, 4, and 19, respectively, said rolls being arranged in staggered order above the lower series of rolls 33, 34, and 35, which are mounted upon shafts 13, 7, and 16, respectively, it being understood 80 by following out the train of gearing (seen in Fig. 1) that the upper series of rolls 30, 31, and 32 will revolve at a faster rate of speed than the lower series of alternate or staggered rolls 33, 34, and 35. 85

It will of course be understood that the rolls above mentioned are mounted in suitable boxes in the frame or housing 36 of the machine and that the desired adjustment of said rolls can be had by manipulating suitable adjusting devices 37 according to requirements, certain portions of the latter being omitted in Figs. 2 and 3 for the sake of clearness of illustration. 90

38 designates ears suitably supported and 100 having set-screws or adjusting devices 39 passing therethrough, said set-screws bear-

ing upon arms 40, which are supported from the shafts 41 in pairs, as will be evident from Figs. 3 and 4, each of said shafts being mounted in suitable bearings and having in contact therewith adjusting-screws 42, which are seated in the levers 43, which are pivoted at 44 to the arms 40.

45 designates the lower scraper, which is supported in the arms 40, the lower edge of 10 said scraper being contiguous to the adjacent rolls 30, 31, and 32 and being serrated or recessed, as will be understood from Fig. 4.

46 designates the upper scraper, which is secured to the levers 43 in any suitable manner and is adapted to contact with the periphery of the adjacent roll at a point above the scrapers 45.

47 designates outer deflecting devices, which are secured to their supports in any suitable 20 manner, as will be understood from Figs. 3 and 5, the direction in which the soap is deflected being indicated by the arrows seen in said latter figure, the perfumery, coloring-matter, &c., and the soap being commingled 25 or concentrated to the desired degree, as will be apparent from the employment of the intermediate wedge or V-shaped deflector 47^X.

48 designates a chute or hopper in which the soap is first placed, the latter after passing 30 through the rolls being received in the rear hopper or deflector 49 and discharged thence upon the endless apron 25.

The operation is as follows: The soap is first placed in the hopper 48, and by reason 35 of the rotation of the rolls 30 to 35, inclusive, in the directions indicated by their arrows it will be evident that the perfumery, coloring-matter, &c., will be thoroughly commingled and the soap will be propelled toward the rear 40 of the machine toward the hopper or deflector 49 and from thence will fall on the apron 25 and be conducted toward the front of the apparatus to any suitable receptacle. Since the rolls 30, 31, and 32 revolve at a higher rate 45 of speed than the rolls thereunder, it will be apparent that the tendency will be to remove the soap from the lower series of rolls and to draw the same upwardly against the deflector 45; by which latter it will be scraped off the 50 upper rolls and will fall upon the lower rolls, as is evident, the soap being at the same time compressed during its passage through the rolls and concentrated by means of the deflectors 47 and 47^X, wherefrom it will be seen 55 that every portion of the soap will be thoroughly commingled and the perfumery, coloring-matter, &c., will be thoroughly and effectively mixed with every portion thereof. The function of the upper scrapers 46 is to 60 remove any of the soap which may pass the scrapers 45, thereby positively preventing said soap from passing entirely around the upper rollers. By manipulating the adjusting-screws 39 and 42 it will be seen that the 65 degree of contact of the scrapers 45 and 46

with the adjacent rolls can be regulated with great exactness. It will thus be seen from the foregoing that by my invention the perfumery, coloring-matter, &c., of the soap and the different ingredients thereof will be thoroughly and expeditiously commingled and by the provision of the scrapers and deflectors every portion of the soap will be thoroughly and effectively treated to the desired extent. 70

Having thus described my invention, what 75 I claim as new, and desire to secure by Letters Patent, is—

1. In an apparatus of the character named, the combination of an upper and lower series 80 of rolls, arranged in staggered order, said upper series being adapted to rotate at different speeds from the lower series and scrapers for said upper series of rolls.

2. In an apparatus of the character named, the combination of an upper and lower series 85 of rolls, said upper series revolving at different rates of speed from the lower series and being arranged in staggered order relative thereto, an endless apron located underneath said rolls, means for revolving the latter and 90 said apron, and scrapers for said upper series of rolls.

3. In an apparatus of the character named, an upper and lower series of rolls, means for revolving said series at different speeds, deflectors located intermediate said series, and upper and lower scrapers for said upper series of rolls, said lower scrapers being provided with a recessed portion. 95

4. In an apparatus of the character named, 100 a series of rolls arranged in staggered order, a shaft arranged above one series of said rolls, said shaft carrying arms, a lower scraper common to said arms, levers pivoted to said arms, an upper scraper carried by said levers and 105 adjusting devices for said upper and lower scrapers.

5. In an apparatus of the character named, 110 an upper and lower series of rolls arranged in staggered order, means for revolving said upper series at a higher rate of speed than said lower series, side and intermediate deflectors located in proximity to said lower series of rolls, a plurality of scrapers located in proximity to each of said upper rolls, means for 115 adjusting said scrapers, a hopper or deflector at the rear portion of the machine, an endless apron located underneath said hopper and means for actuating said apron and said rolls.

6. In an apparatus of the character named, 120 a main shaft 1, a pinion 2, carried thereby, a gear 3 meshing with said pinion, a shaft 4 on which said gear is mounted, a pinion 5 mounted on said shaft 4, a gear 6 meshing with said pinion, a shaft 7 on which the gear 6 is mounted, a gear 8 mounted on the shaft 7, a gear 9 meshing with the gear 8, a shaft 10 carrying said gear 9, a gear 11 mounted on the shaft 10, a gear 12 meshing with the gear 11, a shaft 13 carrying the gear 12, a gear 14 mounted on 130

the shaft 4, a gear 15 meshing with said gear 14, a shaft 16 carrying said gear 15, a gear 17 mounted on the shaft 16, a gear 18 meshing with the gear 17, a shaft 19, on which said gear 18 is mounted, said shafts 10, 4 and 19 being arranged out of alinement with the shafts 13, 7 and 16, and rolls mounted on said

shafts, the upper series of rolls and shafts being adapted to revolve at a higher rate of speed than the lower series.

FRANCIS S. RUTSCHMAN.
